FIG. 10 is view of the fragmentary enlarged front view of
FIG. 6 highlighting the grooves.

In FIG. 10 the solid contrast is for the purpose of highlighting
the grooves. The black contrast is for the purpose of
highlighting the deepest grooves, and the gray contrast is for
the purpose of highlighting the less deep grooves.

In the drawings, the broken lines are for defining the
sidewall, inner bead and the boundary between the claimed
tire tread and the unclaimed sidewall, and form no part of the
claimed design.
